UNITED STATES PATENT OFFICE.

WILLIAM HUNTRESS, OF SOUTH BERWICK, MAINE.

BEDSTEAD.

Specification of Letters Patent No. 15,076, dated June 10, 1856.

To all whom it may concern:

Be it known that I, WILLIAM HUNTRESS, of South Berwick, in the county of York and State of Maine, have invented a new and useful Improvement in Bedsteads; and I hereby declare the following to be a full and exact description thereof, reference being had to the drawings herewith presented, which drawings constitute a part of said 10 description.

My invention consists in providing a bedstead as hereafter described with a register windlass foot rail and a lever for the purpose of straining and fastening a bottom 15 tom of cords, pins and slats, having a smooth level surface.

Great objection to the common windlass bedstead arises from the unevenness occasioned by the cord being interwoven with or 20 crossing over the slats and by such unevenness rendering the bed uncomfortable and wearing out the mattress or ticking in certain parts; whereas by my invention all 25 these objections are obviated, the surface of the slats is rendered perfectly smooth and level by placing the cords all below the slats and by placing the foot-rail or windlass (C,) half its diameter lower than the side rails, while my slats are kept in place by 30 the broad headed pins (P, P,) placed in the under side of the slats near each end and interlaced with the cords as seen at (Fig. 3,) the slats may be placed so near together as to present one continued surface and all 35 the elasticity of the cords end of the slats is preserved in its full extent; at the same time the bedstead is more convenient to use being more readily taken apart and set up again whenever it is to be removed from 40 room to room.

To enable others to make and use my invention I proceed to describe its construction as follows.

I construct the head and foot of the bed- 45 stead in the usual manner but I glue the head and foot boards to the posts of the bedstead. I make the head rail fast to the posts so it cannot be moved.

The side rails (B and B, Figure 1,) are 50 placed on the same plane with the head rail; they are framed into the posts so that they may be removed at will from the head and foot. At the foot I place a round rail

or windlass (C, Fig. 1.) This footrail is not on the same plane with the side rails 55 but placed half its diameter lower at top than the side rails. On the side of the rail or windlass I place two strong broad headed pins (D, D,) see the drawings Fig. 1, is an isometrical view of the bedstead.

Similar letters refer to the same parts in each figure.

Around the windlass near each end I cut the grooves (E E) in order to keep the cords in their places. I bore holes (o o,) at 65 equal distances around the middle of the windlass for the purpose of inserting the lever (L). This lever may be inserted or removed at will but is used for a permanent fastening. At the ends of the head rail 70 are cut also grooves similar to those in the foot rail or the head rail may be made the windlass instead of the foot rail. Fig. 2 shows a section of the windlass (C,) and the lever (L,) secured by the chain (Y,) at- 75 tached to the under side of the slat (S;) but when the head rail is the windlass then the lever may rest against the back of the head board.

The advantages of this mode of construct- 80 ing bedsteads are the facility with which the bottom is strained, the rapidity with which the bedstead can be put up and taken down, and the increased convenience in making up 85 the bed by having the footrail let down so as to give more room between the rail and the foot board; the pins with which the cords interlace prevent the slats from working endwise, which present a uniform even surface; they create no friction upon the cord 90 and less wear to the ticking or mattress than the old device of lacing over and under the slats. The lever and chain makes a neater finish, is less expensive, and less liable to get 95 out of repair than the old device of fastening with a ratchet and pawl.

When I use this bedstead I tie the ends of the cord around the head rail and hitch the loop or double of the cord on the pin (D,) which is on the windlass (C,) shown at Fig. 100 2. I make the second or third slat from the windlass thicker in the middle than at the ends for the purpose of resisting the action of the lever (L). To the middle of this slat there is a small chain or knotted cord by 105 which the lever is held in its place.

I do not claim the cords, slats, windlass, or any of the parts when used in the manner in which they have before been used; but

5 What I claim as my improvement and desire to secure by Letters Patent is—
The pins P, P, when placed in the under

side near each end of the slats and interlaced with the cords as above described.

WILLIAM HUNTRESS.
